(57) **CLAIM**

The ornamental design for a display screen with a graphical user interface element, as shown and described.

DESCRIPTION

The sole FIGURE is a front view of a display screen with graphical user interface element of the new design.

The outermost broken lines in the FIGURE show a display screen and form no part of the claimed design. The other broken lines in the FIGURE show portions of the graphical user interface that form no part of the claimed design.

1 Claim, 1 Drawing Sheet
